UNITED STATES PATENT OFFICE.

LAWRENCE A. MURPHY, OF ST. JOHN, NEW BRUNSWICK, CANADA.

CAR-COUPING.

1,382,530.

Specification of Letters Patent. Patented June 21, 1921.

Application filed August 9, 1920. Serial No. 402,475.

To all whom it may concern:

Be it known that I, LAWRENCE A. MURPHY, a citizen of the Dominion of Canada, residing at St. John, in the county of St. John and Province of New Brunswick, have invented 5 certain new and useful Improvements in Car-Couplings, of which the following is a specification.

This invention relates to improvements in 10 car couplers and is particularly designed for use in railroad practice, and the objects of the invention are to permit of cars being readily coupled together, to arrange the several parts of the coupler so that they will 15 be capable of ready inspection, to render the coupler easily detached and to permit it to better perform the functions required of it.

The invention consists of the novel features, details of construction, and combination 20 of parts which hereinafter will be more particularly set forth, illustrated in the accompanying drawings and pointed out in the appended claims.

In the drawings, Figure 1 is a plan view 25 of the improved coupler.

Fig. 2 is a side elevation of the improved coupler.

Fig. 3 is a longitudinal section of the coupler.

30 Fig. 4 is a longitudinal section of the coupler showing the movable arm in an open position.

Fig. 5 is a perspective view of the cam which controls the movement of the movable 35 arm.

Fig. 6 is a perspective view of the movable arm.

Similar characters of reference indicate like parts throughout the drawings.

40 Referring to the drawings, A represents the improved coupler comprising a guard arm 1 formed integral with a shank 2, which is provided with flanged ends 3.

The guard arm is provided with a horn 45 4 adapted upon inward movement of the coupler to strike the end sill or a striking casting, the shank being provided with a shouldered butt for connection with a yoke. The shank and body portion of the coupler

50 are formed hollow, and in the outer end a rotatable conical member 5 is journaled, the lateral wall of the rotatable member being formed arcuate and having a spiral cam race 6 therein. Said member 5 constitutes a 55 combined lock and knuckle thrower.

The smaller end of the rotatable member

5 has its outer periphery cut away as shown at 7, and a spindle 8 extends from the said member through the lateral wall of the coupler and is adapted to be attached to any 60 suitable actuating means whereby the rotatable member 5 may be rocked backwardly and forwardly as will be explained later.

The body portion of the fixed jaw is formed with tongues 9 on the upper and 65 lower walls and the arm 10 is attached to these tongues by the hinge pin 11.

The coupler may be formed in two parts, as indicated by the center longitudinal line 70 in Fig. 2.

The arm 10 has an inwardly extending end 12, the under face of which is formed with a cam surface 13 and the end of the arm co-acts with the cam race 6 in the rotatable member 5. 75

The outer portion of the arm 10 is hooked to form a jaw and as the arm is rotated on its hinge pin 11, the movable jaw 10 will be closed or opened.

When this coupler is in use and it is desired to open the same, rotary motion is transmitted to the spindle 8 which in turn rotates the member 5, and the cam race 6 co-acting with the inner end of the arm 10 will rock the same about its hinge pin so that 85 the movable arm will assume a position when locked as is illustrated in Figs. 1 and 5.

If the arm 10 is rocked in the opposite direction by rotating the member 5 in a contrary direction to that above explained, then the arm 10 will be opened as illustrated in Fig. 4. 90

The opening and closing of the movable jaw of the coupler can be readily accomplished by a trainman when standing outside of the tracks by means of any suitable mechanism attached to the spindle 8. 95

The lock may be assembled with the coupler head by separating the two parts of the latter, inserting the lock, and then securing the said two parts together. 100

What I claim as my invention is:

1. A car coupler comprising a body portion having a fixed jaw, a member rotatably 105 mounted in the body portion having an arcuate lateral wall and a portion of the periphery cut away and a cam race formed on the said member, an arm pivotally mounted to the body portion and having an inwardly extending end having cam surface co-acting with the cam race on the rotatable member, 110

the outer end of the arm being bent to form a jaw as and for the purpose specified.

2. A car coupler comprising a body portion having a fixed jaw, a member rotatably mounted in the body portion and extending transversely thereacross and formed with a cam race and having its outer periphery cut away, a movable jaw pivotally mounted to the body portion having an inwardly ex-

tending end and formed with a cam surface 10 with an inclined wall and co-acting with the rotatable member.

In testimony whereof I affix my signature in the presence of two witnesses.

LAWRENCE A. MURPHY.

Witnesses:

THOMAS L. KILLEEN,
JOHN SULLIVAN.
